UNITED STATES PATENT OFFICE.

THOMAS T. McGUIRE, OF COLUMBUS, OHIO.

ADHESIVE-TAPE MACHINE.

1,289,213.

Specification of Letters Patent. Patented Dec. 31, 1918.

Application filed February 18, 1918. Serial No. 217,896.

To all whom it may concern:

Be it known that I, THOMAS T. McGUIRE, a citizen of the United States, residing at Columbus, in the county of Franklin and State 5 of Ohio, have invented certain new and useful Improvements in Adhesive-Tape Machines, of which the following is a specification.

This invention relates to an apparatus 10 for supporting and dispensing adhesive tape and like materials, and has for its object to provide a simple and efficient device wherein a reel of tape may be rotatably supported and to provide coöperative means for 15 moistening the adhesive surface of the tape as the latter is withdrawn from the reel.

Another object of the invention is to provide a shearing device upon the apparatus and to locate said device in spaced relation 20 from a structure for exerting special tension upon the tape so as to guide the latter over a moistening roller, whereby the sheared end of the tape may be conveniently grasped to effect a further withdrawal of the tape from 25 the reel structure.

A further object of the invention resides in an apparatus of the above character possessing substantial and sanitary features of construction, and wherein the font for supplying the roller with moisture will be 30 constantly covered so as to prevent the arising of odors from fluid contained within said font.

With these and other objects in view as 35 will appear as the description proceeds, the invention accordingly consists in the novel features of construction, combination of elements, and arrangements of parts hereinafter fully described and of the scope thereof 40 indicated in the claims hereunto annexed.

In the drawing, wherein has been shown the preferred embodiment of the invention,

Figure 1 is a top plan view of the tape supporting apparatus comprising the present invention, parts of the apparatus being 45 shown in sections.

Fig. 2 is a vertical, longitudinal sectional view taken along the line 2—2 of Fig. 1.

Fig. 3 is a transverse cross-sectional view, 50 the plane of which being disclosed by the line 3—3 of Fig. 1.

Similar characters of reference denote corresponding and like parts throughout the several views of the drawing.

55 Referring more particularly to the details

of the invention, the improved tape supporting and dispensing apparatus A, comprising the preferred form of the invention, consists of a body gear formed in the nature of an integral casting. The latter is formed 60 to provide a central, longitudinal extending opening 2, from the side walls of which depend bearings for the reception of the shaft 3 of a reel drum 4, and upon which drum is mounted a reel of adhesive tape 5. The tape 65 may be employed for any suitable purpose, and is usually utilized in securing or fastening packages in lieu of string or cord, the tape as usual having the under surface thereof provided with a suitable adhesive, which 70 may be moistened and applied to the desired places.

The forward end of the body 1 is reduced to provide a roller receiving well 6, in which is rotatably supported a porcelain or glass 75 roller 7, which latter being considerably wider than the tape 5. The roller is provided with an axial shaft 8, and has the extremities thereof positioned within sockets 9 formed in the side walls 10 of the well, 80 this construction permits the roller to freely revolve. Water or other like fluid is supplied to the well in abundant quantities by providing the sides of the body 1 with a plurality of spaced water containing compartments 85 11, which are in communication as at 12 with the well 6, thus insuring an adequate supply of water for effecting the successful operation of said roller.

The rear wall of the well 6 terminates at 90 its upper end in a ledge 13, over which the free extremity of the tape reel passes while turned over the roller 7. This extremity of the reel is maintained in engagement with the ledge through the provision of a leaf 95 spring 14, which bears directly upon that portion of the tape passing across the ledge 13, and thus prevents the free end of the reel from assuming a relatively inaccessible position, as will be clearly understood. In 100 this instance the spring 14 is secured in its operative position by connecting the upper end of the same with a shelf 15, integrally formed upon the top of the body 1. The shelf is equipped with an elongated slot 16, 105 in which is positioned the upper offset extremity of the spring 14, and it will be evident that the tension exerted by the spring upon the ledge 13 will be sufficient to maintain said spring in its operative position. 110

By pressing upon the free extremity of the tape 5, it will be obvious that it will be practically impossible for such extremity to assume an inaccessible position to the rear of 5 the roller 7.

After the tape has been moistened by the roller the same may be severed from the body of the tape carried by the drum 4, through the provision of a shearing member 10 17, which latter is rigidly mounted upon the shelf 15, and has a knife edge thereof positioned in vertically spaced relation with regard to the ledge 13. This location of the shearing member is exceedingly advantageous 15 in that, after the tape has been severed, there still remains a loose end of the tape which may be conveniently grasped and is of great aid in unwinding desired lengths of the tape from the reel 4, as will 20 be clearly understood.

From the foregoing it will be apparent that there is provided a device whereby the objects of the invention have been achieved, and that all of the advantageous features of 25 construction above mentioned are, among others, present. In this form of the invention the body 1 is provided with a rear wall 18, which may be associated with any suitable vertical support so that the apparatus 30 will be maintained in its operative or supported position. Of course, it will be understood that the invention may be supported in any other suitable manner from that described. It will be noted that the fluid contained 35 within the apparatus, for moistening the roller 7, is inclosed by the peculiar construction of the apparatus, thus precluding the arising of objectionable odors from such fluid. The device is of simple construction, 40 reliable in operation, does not include deli-

cate parts which may readily become out of order and can be economically manufactured.

Having described the invention, I claim:

1. An adhesive tape supporting device, 45 consisting of a body portion formed to include bearings for the support of a tape reel, said member including spaced longitudinally extending water containing compartments terminating in a forwardly located common roller well, a moistening roller situated within said well, resilient means tending to maintain the free extremity of said tape reel in a position for co-operation with said roller, and a shearing element carried by said member and spaced from said resilient means. 50

2. An adhesive tape supporting and dispensing device, consisting of a casting formed to include means for supporting a 60 tape reel, a ledge formed upon said casting, resilient means tending to maintain the free extremity of said tape in engagement with said ledge, and moistening roller situated to engage the adhesive surface of said tape as 65 the latter is unwound from said reel, and a shearing element entirely independent of said resilient means carried by said casting and spaced an appreciable distance from said roller. 70

3. An adhesive tape supporting device consisting of a body formed of spaced longitudinally extending water containing compartments in communication with a forwardly located roller well, a roller in said 75 well, and means for supporting a roll of adhesive tape in a space between said water containing compartments.

In testimony whereof I affix my signature.
THOMAS T. MCGUIRE.
